UNITED STATES PATENT OFFICE.

ROBERT L. DORAN, OF CHICAGO, ILLINOIS.

DESIGN FOR AN OIL-BURNER.

55,028.

Specification for Design.

Patented May 4, 1920.

Application filed September 15, 1919. Serial No. 324,036. Term of patent 3½ years.

To all whom it may concern:

Be it known that I, ROBERT L. DORAN, a citizen of the United States, residing at Chicago, in the county of Cook and State of Illinois, have invented a new, original, and ornamental Design for Oil-Burners, of which the following is a specification, reference being had to the accompanying drawing, forming part thereof.

The figure is a perspective view of an oil burner showing my new design.

I claim:

The ornamental design for an oil burner as shown.

ROBERT L. DORAN.
